UNITED STATES PATENT OFFICE

JAMES HARTNESS, OF SPRINGFIELD, VERMONT.

TURNING-TOOL FOR LATHES.

SPECIFICATION forming part of Letters Patent No. 769,219, dated September 6, 1904.

Application filed December 19, 1902. Serial No. 135,871. (No model.)

To all whom it may concern:

Be it known that I, JAMES HARTNESS, of Springfield, in the county of Windsor and State of Vermont, have invented certain new and useful Improvements in Turning-Tools for Lathes, of which the following is a specification.

This invention has relation to turning-tools for lathes, and has for its object to provide a tool of the character described with means whereby the cutter may be set at any one of a predetermined number of positions.

In carrying out the object of the invention I have made in addition provisions for adjusting the abutments which regulate or determine the position of the cutter, so that the tool is adapted for performing any series of turning operations upon the work that may be desired.

As illustrated upon the drawings and as subsequently described, I may employ a plurality of cutters—two, for instance—mounted in a suitable holder, which is adjustable to present either one of the cutters to the work. In this way I provide for producing different shapes of shoulders on the work, either curved or square, as the case may be. The holder for the cutters may be detachably mounted in the casting which forms the body of the tool for the removal and insertion of the cutters, and it may be secured in different positions, as previously stated.

To coöperate with the cutter I provide an abutment or back-rest for the work, which in bar-working machines determines the diameter of the finished work or the depth of the cut. To prevent any inaccuracy in the cutting operation, this abutment or back-rest is in sliding engagement with the work, and it is arranged directly opposite the cutter.

The tool is provided with devices by means of which it may be set in any one of a predetermined number of positions corresponding to the positions of the cutter.

The stops for the back-rest are detachable and adjustable, so that provision is made for holding the back-rest in any one of a plurality of series of predetermined positions.

In addition to the back-rest there is provided a top or thrust rest, which is located

between the point of contact of the back-rest and the contact of the tool with the work. This thrust or top rest takes the burden of the thrust where a properly-ground cutter is employed, and inasmuch as the heat generated by the friction of the rest usually cuts down the speed at which the work may be rotated nearly fifty per cent. the said rest is constructed in the form of a roll, the location of the said roll being such that even if a small particle or chip should get between it and the work the latter would not be forced materially against the cutter, so as to cause the latter to dig into the work. The back-rest and the thrust-rest are formed on or secured to a suitable holder or carrier, which is adjustable to provide for the back-rests either preceding or following the cutter, according to the exigencies of the case.

Additional mechanism is provided for so adjusting the carrier or holder that the two rests may accurately engage the work.

In addition to these features which I have briefly enumerated the invention consists of certain features of construction and arrangement of parts, which are illustrated in the drawings above referred to and pointed out in the following specification.

On the drawings, Figure 1 represents in front elevation a turning-tool constructed in accordance with my invention. Fig. 2 represents a side elevation of the same. Fig. 3 represents a plan view of the tool. Fig. 4 represents the tool partially in section and illustrates the position to which the rest carrier or holder may be adjusted. Fig. 5 represents a view of the other side of the tool. Fig. 6 represents a section on the line 6 6 of Fig. 1. Fig. 7 represents a section on the line 7 7 of Fig. 6. Fig. 8 represents a section on the line 8 8 of Fig. 1. Fig. 9 represents a transverse vertical section through the tool. Fig. 10 represents the cutter holder or carrier and the means for determining the position thereof. Fig. 11 represents a section on the line 11 11 of Fig. 9 looking in the direction of the arrow. Figs. 12 and 13 show the means for securing the cutters in the holder or carrier.

On the drawings the body of the tool is in-

dicated as a whole at 20. It has a flat base with a tongue 21 to enter a groove in the turret of the lathe in case the tool be secured thereto, as indicated in Fig. 1, in which event 5 bolts 23 are passed downward through apertures in the body into sockets in the turret. The body is formed with an aperture 22 to receive the work, and it is provided with strengthening-webs 24, which project rearwardly at its sides.

In an inclined guideway 26, formed in the body, there is placed a cutter-holder 27, which is adapted to slide toward and from the aperture 22. Said holder is in the form of a cylinder with flattened sides, one side being exposed to view from the front of the machine, the guideway 26 being open for this purpose. In each of the flat sides of the holder 27 there is formed a groove 28. One wall of each of 10 the grooves is undercut, as indicated in Fig. 13, and the other is first undercut and then beveled. In these grooves are placed two cutters 29 and 30, respectively, said cutters being so constructed that one will form a 15 square shoulder and the other will make a rounded cut to form a round shoulder. The cutting edges of the cutters project in opposite directions, so that when one of the cutters is in operative position, as shown in Fig. 1, the edge of the other cutter is in an inoperative position, as shown in Fig. 9. By removing the holder with the hands it may be 20 replaced, so that either cutter will be presented to the work as desired. Said cutters 25 are so formed as to fit snugly within grooves 28, formed for their reception, and each one is held accurately in the position to which it may be adjusted by a locking-pin 31, having one end abutting against the cutter and its 30 other end beveled, as shown in Fig. 12. A screw 32 bears against a wedging-pin 321 in engagement with the beveled end of each of the locking-pins 31, so that when it is forced inward the locking-pin is wedged tightly 35 against the cutter so as to hold it in position.

The cutter-holder as a whole is adapted to be moved rectilinearly toward the work against the pressure of an incased spring 33. This spring is placed in a tube or casing, one 40 end of which is closed, said casing being located in a socket formed in the body 20 of the tool-holder. The casing for the spring also fits within a groove formed in the inner end of the cutter-holder, and said casing therefore locks the said holder against rotative movement and preserves the accurate relationship of the cutter and the work.

For moving the said holder to desired position an actuator is employed, comprising a 45 bar 35, having a handle 36. The said bar is pivoted in ears formed on the head of a screw 37, passed through the body or frame 20 of the tool. On its two edges the bar 35 is formed with two cams or projections 38 39, either of which may be brought into engage-

ment with the end of the tool-holder, as best shown in Fig. 1, for the purpose of forcing the said tool-holder against pressure of the said spring 33 toward the work. The screw 37 may be given a half-turn in either direction, so as to bring either operative projection 38 39 into engagement with the said holder. The projections are so formed that one of them will force the tool-holder farther toward the work than the other. 75

For holding the handle 36 in any one of a plurality of positions the frame or body 20 is provided with a plurality of adjustable screws 40. These screws are placed in brackets 41 42, formed on or attached to the frame 80 or body 20, and their edges are separated to permit the handle to be moved upward between them for its reversal. The screws 40 are so placed or located that the bar 35 may occupy a position under any one of them without being engaged by either of the others. The said screws are adjustable in a direction substantially toward and from the work, so that the location of the lower end of each determines the position occupied by the bar 35 85 when it is engaged therewith, the said bar 35 being adapted to swing laterally for this purpose. Each of the screws 40 may be held in place by a locking or set screw 43, arranged transversely thereto. By this construction it 90 will be seen that the tool may be adjusted to any one of eight positions by reversing said bar 35 and locating it under said screws. The brackets 42 are so located as not to interfere with the free removal and partial rotation of 95 the tool-holder, as shown in Fig. 10.

In conjunction with the tool-holder there is provided a carrier or holder for the back-rest and the thrust-rest, to which reference has been hereinbefore made. The said carrier is 100 indicated as a whole at 43. It is pivoted upon an eccentric-pin 44, projecting from a longitudinally-movable rock-shaft 45, journaled in the frame or body directly above the work-aperture 22, as shown in Fig. 9. The said 105 carrier is adapted to be held yieldingly away from the work by a spring-pressed pin 46, whose upper end is in engagement with a stud 47, projecting rearwardly from the carrier, as shown in Figs. 1, 3, and 9. The back-rest 110 is afforded by the inner edge of the carrier, as indicated at 48, although it may be formed separately and secured thereto. This back-rest 48 is substantially directly opposite the edge of the cutter when the latter is in operative position. The thrust-rest consists in the present embodiment of the invention of a roller 49, which is journaled upon a screw-stud 50, projecting forwardly from the carrier 43. The point of engagement of the thrust-rest with the work is between the points of engagement of the cutter and the back-rest with the work. The curve of the back-rest is greater than the peripheral curve of any work that is adapted to be passed through the 115 120 125 130

work-aperture 22 and is such that irrespective of the position of the carrier 43 or the diameter of the work the work will be engaged at two points without independent adjustment of the rests.

The curve of the back-rest is arbitrary; but it is formed so that as the carrier is swung toward and from the axis of the work to bring the rest into engagement with the work said rest will engage the periphery of the work at a point substantially diametrically opposite the point of engagement of the cutter with the work. The top rest is, as stated, pivoted to the carrier, and its periphery projects beyond the curved inner edge or surface of the carrier, so that the roll engages the work at a point between the point of engagement of the cutter and the back-rest and takes the thrust of the cutter. By means of this construction the carrier may be swung about its pivot to accommodate large or small sizes of work, and in each case the work will be accurately engaged at the proper points by both rests without the necessity of adjusting each rest independently of the other, as has hitherto been necessary. For the purpose, however, of bodily adjusting the carrier 43, and therefore the rests, in a direction substantially transverse to the movement of the carrier about its axis in case the rests are unevenly worn the rock-shaft 45 may be rotated. To this end it is provided with an upwardly-projecting handle 51, adapted to rest against either one of a pair of adjustable stops 52 53, said stops being in the form of screws passed through a rearwardly-projecting pin 531, carried by the frame or body 20. The said handle 51 is held against said screws or stops by the spring-pressed pin 46, hereinbefore referred to. For the purpose of engaging the handle with either one of said stops the rock-shaft 45 is longitudinally movable to either of two different positions. The said shaft is provided with two circumferential grooves 54 54, connected by a longitudinal groove 55. A spring-pressed pin 56 in the standard or frame projects into one or the other of the grooves 54 to hold it against longitudinal movement with the handle 51 in line with either of the stops 53. By moving the rock-shaft to abnormal position the groove 55 may be brought into alinement with the pin 56 to permit the longitudinal movement of the shaft 45.

For the purpose of supporting the lower free end of the carrier in either position to which it may be moved by reason of the longitudinal movement of the rock-shaft 45 the said end of the carrier is provided with a rocking pin 57, having an eccentric head 58, which may be engaged with a groove 59, undercut in the face of the frame or standard. The pin 57 is adjustably mounted in the carrier, but is adapted to be readily secured therein by a set-screw 60 after the carrier has been bodily

adjusted in a direction of movement longitudinal of the axis of the work. The engagement of the head 58 of the pin 57 in the groove 59 when the parts are in operative position prevents any loose play of the carrier longitudinally of the work and takes whatever strain may occur by reason of the movement of the tool as a whole relatively to the work.

From this description it will be seen that the rest-carrier is adjustable toward and from the work in lines at right angles to each other to accommodate variations in the diameter of the work.

For the purpose of moving the carrier about its axis toward and from the work and for locating it at any one of a plurality of positions corresponding to the positions occupied by the tool-holder the following mechanism is provided: By reference to Figs. 3, 6, and 9 it will be observed that there is journaled in the standard below the work-aperture 22 a sliding bar 63, having a handle 64. This bar is arranged at right angles to the work, and it is provided with a groove 65 to receive the head 58 of the pin 57, carried by the carrier 43, so that by moving the said bar 63 longitudinally the said carrier may be swung about its axis toward and from the work. The said bar 63 is provided with a laterally-projecting pin 66, which may be brought into alinement with the end of any one of a plurality of adjustable screws 67, arranged in a curve around the bar 63 and projecting inwardly from the rear side of the standard. Each of the said screws 67 is adapted to be secured in position by a set-screw 68.

As has already been said, the spring-pressed pin 46 tends to move the carrier 43 away from the work, and the spring is strong enough to hold the projecting pin 66 against the end of the screw or stop 67 with which it may be in alinement. The screws 66 may be adjusted toward and from a vertical plane passing through the axis of the work, and hence by rotating the bar 63 so as to bring the pin 66 into alinement with the end of any one of said screws the rest-carrier may be quickly brought to a predetermined position with relation to the work.

I have hereinbefore referred to the part 48 as the "back-rest," as that is the name which is usually employed for the rest which is directly opposite the edge of the cutter and which serves to hold the work against lateral movement by reason of the engagement of the cutter therewith. The said part may, however, be termed the "size-determining rest," inasmuch as the said surface determines the size of the work. This part is preferably a smooth surface in sliding engagement with the work.

The roll 49 has been termed the "thrust-rest," although with the present embodiment of the invention it may be called the "top

rest," it being readily understood, however, that it could be located on the other side of a line connecting the points of engagement of the cutter and the size-determining rest with the work. The roll 49 takes the burden of the thrust, and since the heat generated by the friction of the rest usually cuts down the speed at which the turner may be run the employment of the roll prevents the generation of heat.

Where two rests—a size-determining rest and a thrust-rest—are both in sliding engagement with the work, heat is generated, as stated, to a greater extent than is desirable, whereas where both rests are in rolling contact with the work the chips are apt to work down between the work and the size-determining rest and force the work toward the cutter, so that the latter forms deep gouges or cuts therein, which greatly injure the work. According to the present invention, however, the size-determining rest is in sliding engagement with the work and the thrust-rest is in rolling engagement with the work, since a sliding movement of the work in a line parallel to a tangent to the periphery of the work at the point of engagement of the cutter therewith would not cause the cutter to injure the work. Both of these rests are mounted upon a single carrier, which is pivoted to the main frame and which is therefore easily adjusted about its pivot and fixed at any desirable point in its adjustment, all without, as previously stated, requiring the independent adjustment of either one of the rests. The adjustable stops 52 and 53 provide for bringing the rests properly against the work to insure the perfect contact of each.

The employment of the eccentric-pin, the longitudinally-movable shaft 45, and the stops is for permitting a slight withdrawal of the top and back rest in the removal of the tool from the work and to furnish an auxiliary means for bringing the top and back rest forcibly into position after the bar 63 of the carrier has been adjusted.

Referring once more to the cutters 29 and 30, it will be seen that each is in the shape of a bar, with two flat parallel sides *a* *b*, the side *b* being wider than the side *a*. The bottom of the cutter has a single bevel to provide a large area to that part of the shank which takes the thrust. The top of the cutter has a V-shaped groove, which not only furnishes a cutting edge, but also provides a bevel *c*, so that the cutter may fit in the dovetail groove in the holder. The clamp 31 engages the cutter-shank on the side *b* near the top; but when a single cutter is placed in the holder the location of the clamp may be changed. It is apparent that the arrangement of the screws 32 in parallelism with the cutters makes a very convenient and simple construction.

It will be understood that various changes

may be made in the particular embodiment of the machine herein illustrated and that various parts of the invention may be employed separately or independently of other parts.

Having thus explained the nature of the invention and described a way of constructing and using the same, although without attempting to set forth all of the forms in which it may be made or all of the modes of its use, I declare that what I claim is—

1. A turning-tool comprising a size-determining or back rest, a thrust-rest, a swinging carrier for said rests, and means including an eccentric pivot for said carrier, by which the carrier may be adjusted with relation to the work. 75

2. A turning-tool, comprising a main support, a cutter thereon, a carrier pivoted to the support and adjustable about its pivot, said carrier having a size-determining rest substantially diametrically opposite the point of the cutter, and also having a roller thrust-rest journaled thereon and arranged to bear on the work between the size-determining rest, and the cutter to resist the thrust of the cutter, and means for engaging and holding the free end of said carrier at different points in its adjustment. 85

3. A turning-tool comprising a support, a cutter on said support, a carrier pivoted to the support and movable toward and from the work and having a curved surface opposite the cutter, said curved surface being such that it engages the work to serve as a sliding rest for the work substantially opposite the cutter irrespective of the diameter of the work and means for fixing the free end of the carrier. 95

4. A turning-tool comprising a cutter, a carrier having a curved edge opposite the cutter and spaced therefrom to permit the passage of the work between them and adapted to operate as a size-determining rest, and a roller journaled on the carrier and having the periphery projecting beyond the size-determining rest to engage the work and serve as a thrust-rest, and means for fixing the free end of said carrier. 100

5. A turning-tool comprising a size-determining rest, a thrust-rest, a pivoted carrier for both of said rests, and means for adjusting said carrier in lines toward and from the work, and in lines intersecting the first-mentioned lines. 110

6. A turning-tool comprising a size-determining rest, a thrust-rest, a pivoted carrier for said rests, means for adjusting said carrier about its pivot toward and from the work, and means for adjusting said pivot to move said carrier and the rest tangentially of the work. 115

7. A turning-tool comprising a frame, a cutter, a work-rest, a movable carrier for the said rest, and a plurality of independent de-

- vices each adapted to hold said carrier in a separate predetermined position independently of the other devices.
8. A turning-tool comprising a frame, a cutter, an adjustable work-rest, and a plurality of independent stops for holding said rest successively in a plurality of predetermined positions, independently of each other.
9. A turning-tool comprising a frame, a cutter, an adjustable work-rest, a plurality of adjustable stops or abutments on the frame, and means for engaging said rest with any one of said stops or abutments independently of the others, and thereby effecting a multiple adjustment of said rest.
10. A turning-tool comprising a frame, a cutter, an adjustable work-rest, a plurality of stops or abutments on said frame, and an oscillatory member connected to said work-rest and adapted to be engaged with said stops.
11. A turning-tool comprising a frame, a cutter, a work-rest adjustable toward and from the work, and independent adjustable stops or abutments for resisting the thrust of the rest in the described lines of adjustment of the said rest independently of each other.
12. A turning-tool comprising a frame having provisions for attachment to a lathe-slide, a cutter-holder adapted to slide on the frame, a lock on said frame, a lever bearing upon said cutter-holder, and a universal joint connecting said lever to said frame whereby said lever is movable longitudinally of said holder, and is movable laterally thereof to be engaged with said lock.
13. A metal-turning tool for turret-lathes comprising a frame having means for attachment to a turret, a holder on said frame movable substantially perpendicularly to the work-axis, and rotatively adjustable about an axis parallel to its lines of movement, cutters projecting in the same direction and secured to said holder in parallelism to each other and to the line of movement of said holder, and means for securing said holder in said frame.
14. A metal-turning tool for lathes comprising a frame having provisions for attachment to a lathe, a longitudinally-movable holder in said frame adjustable about its longitudinal axis, which is transverse to the work-axis and cutters secured to said holder in parallelism to each other and to said longitudinal axis, said cutters having their edges projecting in the same direction.
15. A turning-tool comprising a frame having provisions for attachment to a lathe-carriage, a cutter-holder having a plurality of parallel cutters, provisions whereby said holder may be rotated to bring a cutter thereon to operative position with relation to the axis of the work, and means for moving said holder in lines longitudinal of its axis of rotation and parallel to the cutters to advance the cutter transversely with relation to the work-axis.
16. A turning-tool comprising a frame having provisions for attachment to a lathe-carriage, a cutter-holder having a plurality of substantially parallel cutters on its sides, provisions for relatively adjusting said holder in said frame about an axis parallel to said cutters to bring any one of said cutters to operative position, and means for moving said holder longitudinally of said cutters and transversely of the work.
17. A turning-tool for lathes comprising a frame with a guideway therein extending transversely of the work-axis, a holder movable in said guideway, provisions whereby said cutter-holder may be rotated about an axis transverse to the work-axis and parallel of the lines of movement of said holder to bring a cutter thereon in operative relation to the work, and having parallel grooves in its periphery for the reception of a plurality of cutters.
18. A turning-tool for lathes comprising a frame, a longitudinally-movable holder in said frame having one or more cutters projecting from one end thereof, a movable-abutment lock connected to the frame and bearing against the other end of said holder to resist the thrust of the work thereon.
19. A turning-tool for lathes comprising a frame, a longitudinally-movable holder in said frame having one or more cutters projecting from one end thereof, a movable-abutment lock connected to the frame and bearing against the other end of said holder to resist the thrust of the work thereon, and a plurality of independent stops to be severally engaged by said lock to maintain the holder in different adjustments.
20. A turning-tool for lathes comprising a frame having a guideway with solid surrounding walls, a holder in said guideway with one or more cutters affixed to the side or sides thereof with their outer surfaces flush with the outer surface of the holder, said cutter or cutters projecting from one end of said holder, and an abutment bearing against the other end of the holder.
21. A turning-tool comprising a frame, having provisions for attachment to a lathe-turret, a movable cutter-holder arranged transversely of the work, a spring against which one end of the holder bears, and a plurality of independent stops on said frame, and a movable lever or abutment attached to said frame to bear against the other end of said holder, said lever or abutment being adapted for engagement with any one of said stops.
22. A turning-tool comprising a frame, having provisions for attachment to a lathe-turret, a movable cutter-holder arranged transversely of the work, a plurality of independent stops or abutments on the frame, and a lock pivoted to said frame, bearing against the holder and adapted to be engaged with any

one of said stops to maintain said holder in any one of a plurality of different positions.

23. A turning-tool comprising a frame having provisions whereby it may be attached to a lathe-turret, a movable cutter-holder, a member on said frame for locking said holder, and a plurality of stops or abutments on said frame for engaging and positioning said member independently of each other.

24. A turning-tool comprising a frame having provisions whereby it may be attached to a lathe-turret, a movable cutter-holder, a member for locking said holder, and a plurality of independent stops or abutments on the frame for singly and separately engaging and positioning said member independently of each other.

25. A turning-tool comprising a frame, a movable cutter-holder, a plurality of independent stops or abutments on said frame arranged in series, and a member for locking said holder and being laterally movable for engagement with any one of said stops or abutments.

26. A turning-tool comprising a frame, a movable cutter-holder, and a reversible member having oppositely-projecting cams of dif-

ferent lengths for engaging and moving said holder.

27. A turning-tool comprising a frame, a work-rest, an oppositely-disposed tool-holder, a plurality of independent devices for effecting independently of each other a predetermined multiple adjustment of said work-rest, and a plurality of independent devices for effecting a corresponding predetermined multiple adjustment of said tool-holder.

28. A turning-tool comprising a frame having an aperture for the work and a socket transverse thereto, a holder in said socket and adapted to be removed, partially rotated and reinserted in said socket, means for preventing the rotation of said holder when it is in said socket, parallel cutters secured in the sides of said holder, and projecting from an end thereof, and means for adjustably securing said holder in said frame.

In testimony whereof I have affixed my signature in presence of two witnesses.

JAMES HARTNESS.
